His Attorney.

UNITED STATES PATENT OFFICE.

EDWARD W. KELLOGG, OF SCHENECTADY, NEW YORK, ASSIGNOR TO GENERAL ELECTRIC COMPANY, A CORPORATION OF NEW YORK.

RADIO RECEIVING SYSTEM.

Application filed April 15, 1922. Serial No. 552,868.

My present invention relates to radio receiving systems and more particularly to an arrangement of antennæ which is especially adapted for radio reception.

5 In my Patent 1,487,339, issued March 18, 1924, I have described a unidirectional receiving antenna made up of two horizontal conductors and have set forth and claimed a means whereby the antenna conductors 10 may be employed as a transmission line for carrying the signaling currents from the point in the antenna where they are strongest to a distant point along the length of the antenna where the receiving station may be 15 more conveniently located. In this case a transformer is provided at the end of the antenna where the signaling currents received are strongest and the signaling currents received upon the two conductors of the antenna in parallel are caused to unite and flow through the primary of this transformer. The secondary of the transformer has its terminals connected to the two antenna conductors so that these two conductors 20 serve as the two sides of a transmission line which conveys the signaling currents back to the other end of the antenna or to any desired point along its length. In practice the primary winding of the 25 transformer is generally connected between ground and a neutral or mid point of the secondary winding.

The object of my present invention is to provide an improvement in the apparatus described whereby the same effect may be obtained without the use of a transformer.

It has been found in practice that the most suitable ratio to employ for the transformer mentioned is a two to one ratio. This 40 means that the currents impressed upon the transmission line by the transformer will be substantially equal in value to the signaling current received upon each conductor. In one of the conductors the signaling current thus impressed upon the transmission line will flow in the same direction as the signaling current received thereon whereas in the other conductor the impressed current will flow in the opposite direction to the signaling current received. The result will be that at 45 the end of the antenna to which the transformer is connected a current of twice the value of the received signaling current will flow in one conductor while the two currents

in the other conductor will substantially 55 neutralize each other.

I have discovered that a substantially similar result may be obtained without the use of a transformer by producing an open circuit reflection in one conductor and a short circuit reflection in the other. This may be accomplished by merely removing the ground connection from one conductor to produce an open circuit reflection therein and connecting the other conductor to ground 60 through as low a resistance as is obtainable, thereby producing a short circuit reflection 65 in that conductor.

The novel features which I believe to be characteristic of my invention are set forth 70 with particularity in the appended claims, my invention itself, however, both as to its organization and method of operation will best be understood by reference to the following description taken in connection with 75 the accompanying drawing in which I have illustrated diagrammatically one way in which my invention may be carried into effect.

As indicated in the drawing, I provide a 80 long antenna made up of two parallel horizontal conductors 1 and 2. Ground connections are provided at the ends 3 and 4 of this antenna, the ground connection at 3 being made through a resistance 5 having a value 85 substantially equal to the surge impedance of the antenna to prevent undesired reflections back over the length of the conductors. An antenna of this type has marked

90 unidirectional properties, the signaling current received on the antenna being of maximum value at the end furthest from the transmitting station, and of minimum value or substantially zero at the end of the antenna nearest the transmitting station. In

95 the present case it is assumed that it is desired to receive signaling waves travelling along the antenna through the ether from the end 3 toward the end 4, but that it is desired to locate the receiving station at or near the end 3 of the antenna. In order to

100 provide means for transmitting the desired signaling currents received upon the antenna which are strongest at the end 4 back toward the end 3. In my prior patent above referred to, I have accomplished this by 105

means of a transformer as described, located at the end 4. In the present case, however, the desired effect may be obtained by open circuiting the end of the conductor 1 at end 4 of the antenna, and directly grounding conductor 2. The result of this arrangement is to produce an open circuit reflection back along the length of the conductor 1, which is superimposed upon the current wave built up on the antenna by the signal in such phase and magnitude as to produce zero current at the end 4 of antenna conductor 1. At the same time a short circuit reflection is produced in conductor 2, which in effect 15 practically doubles the current flowing in that conductor. Thus the opening of conductor 1 and grounding of conductor 2 produces an effect at the end 4 of the antenna exactly equivalent to the effect obtained by 20 use of a transformer, and the effect on the receiving apparatus 9 will also be the same as though a transformer had been employed at the end 4.

The winding 6 of transformer 7 is not affected by currents flowing in the same direction in the two conductors of the antenna, but is affected by currents which flow in opposite directions in the two conductors. The signal waves built up on the 25 antenna flow in the same direction in both conductors, but the waves reflected from the end 4 in the manner described in my present invention, flow in opposite directions in conductors 1 and 2, and therefore affect the receiving set through the transformer 7.

By reason of the resistance in ground connection 4 of the antenna there may be a loss of energy in the short circuit reflection and the reflected current in conductor 2 40 will be less than that in conductor 1. This unbalance will in some cases be detrimental. The difficulty may be overcome by the provision of a leak resistance 10 which may be connected between the end of conductor 1 45 and ground by means of a switch 11. The resistance of this leak 10 should be approximately such that $R_L:Z::Z:R_G$ in which proportion R_L is the resistance of the leak 10, R_G the resistance of the ground, and Z 50 the surge impedance of one conductor with ground return.

While I have shown and described one simple embodiment of my invention, it will be apparent that many modifications in the 55 manner in which it is applied as well as in the location of the receiving apparatus may be made without departing from the scope of my invention as set forth in the appended claims. The use of this invention elimi-

nates all transformer losses and operates 60 equally well for all frequencies it may be desired to receive, which is not true of any transformer.

What I claim as new and desire to secure by Letters Patent of the United States, is: 65

1. The combination in a radio receiving system of a long horizontal antenna made up of two parallel conductors, means at one end of said antenna for producing an open circuit reflection in one of said conductors 70 and a short circuit reflection in the other and means for combining the reflected currents to operate a receiver.

2. The combination in a radio receiving system of a long horizontal antenna made 75 up of two parallel conductors both of said conductors being grounded at one end, and one only of said conductors being grounded at the opposite end and means for supplying to a receiving apparatus currents flowing in 80 the two conductors.

3. The combination in a radio receiving system of a long horizontal antenna made up of two parallel conductors, means at one end of said antenna for producing reflections of different phase in the two conductors 85 and means for combining the reflected currents to operate a receiver.

4. The combination in a radio receiving system of a long horizontal antenna made 90 up of two parallel conductors, receiving apparatus located at one point along said antenna and connected to both of said conductors and means at another point in said antenna for producing reflections of different 95 phase in the two conductors.

5. The combination in a radio receiving system of a long horizontal antenna made up of two parallel conductors, receiving apparatus located at one point along said antenna and means at another point in said antenna for transmitting the energy of received signals over the two conductors to the receiving apparatus comprising means for producing reflections of different phase in 105 the two conductors.

6. The combination in a radio receiving system of a long horizontal antenna made up of two parallel conductors and means at one end of the antenna for producing reflections of different phase over the two conductors and thereby producing a desired effect in receiving apparatus connected across the two conductors at a distant point.

In witness whereof, I have hereunto set 115 my hand this 14th day of April, 1922.

EDWARD W. KELLOGG,
